CLAIM

The ornamental design for a vehicle grille as shown and described.

DESCRIPTION

FIG. 1 is an isometric view of a vehicle grille showing our new design.

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an enlarged detail view thereof.

The broken lines shown in the drawings depict portions of the vehicle grille that form no part of the claimed design. The dash-dot broken lines in FIGS. 1, 2 and 8 define boundaries of the claim and form no part of the claimed design.
